UNITED STATES PATENT OFFICE.

JESSE DAVID PADGITT, OF DALLAS, TEXAS.

HARNESS.

Application filed December 20, 1923. Serial No. 681,865.

To all whom it may concern:

Be it known that I, JESSE DAVID PADGITT, a citizen of the United States, residing at Dallas, in the county of Dallas and State of Texas, have invented certain new and useful Improvements in Harness, of which the following is a specification.

This invention relates to harness and refers more particularly to improvements in the breeching support for harness.

An object of the invention is to provide a support of simple construction and within which the metal rings now commonly used will be eliminated.

15 A second object is to provide a support that may be more quickly manufactured at a smaller cost, thus saving time, labor and expense.

A still further advantage of the invention 20 lies in the support or hip straps which are attached to the back pad.

Other features are the manner of attachment of the turn back straps to the central portion of the breeching support or hip 25 straps, and the manner of fastening the hip straps and back pad together. The above objects and advantages will be clearly set forth in the following description, taken in connection with the drawings attached here- 30 to, as follows:—

Figure 1 represents a sectional top or plan view of the invention.

Figure 2 shows a view of the lower or under side partly broken away.

35 Figure 3 shows the invention in position and its relation to the breeching.

Following the figures, the pad 1 is stitched at α along the edge and has the strap support 2 sewed on its upper surface. This

support is divided into two straps, 4 and 5 40 of equal size, which are in turn stitched at points $y-y$. The straps 4 and 5 are adapted to be attached to the breeching 8 by buckles 9—9 or by any standard attachment.

The turn back straps 3—3, extending to 45 the girth (not shown) are riveted to the upper portion of the strap 2 at points $a-a$. The back pad is stuffed with suitable material 6, preferably hair or wool.

It should be understood that the strength 50 and size of the straps may vary and the amount of stitching be adapted to the style of the harness whether light or heavy, without departing from the spirit and intent of the invention as set forth in the following 55 claims:—

1. In a harness, a breeching support comprising a back pad; a supporting strap stitched to the back pad and situated above it, said strap being split longitudinally on 60 each side of its attachment to the pad to form two straps, means to attach the end of the straps so formed to a standard breeching, and turn back straps fastened over the back pad and supporting strap. 65

2. In a harness, a breeching support comprising a back pad, a support strap stitched to the back pad on its upper side; said strap divided into two breeching straps on either side of said attachment; means to attach 70 ends of the breeching straps to a standard breeching, and means to attach a turn back strap or straps to the support strap and the back pad.

In testimony whereof I have signed my 75 name to this specification.

JESSE DAVID PADGITT.
